UNITED STATES PATENT OFFICE.

ADOLPH L. DE LEEUW, OF HAMILTON, OHIO, ASSIGNOR TO THE NILES TOOL WORKS COMPANY, OF HAMILTON, OHIO.

SPEED-CHANGER.

SPECIFICATION forming part of Letters Patent No. 764,115, dated July 5, 1904.

Application filed March 28, 1904. Serial No. 200,267. (No model.)

To all whom it may concern:

Be it known that I, ADOLPH L. DE LEEUW, a citizen of the United States, residing in Hamilton, Butler county, Ohio, (post-office address, 5 care Niles Tool Works Company, Hamilton, Ohio,) have invented certain new and useful Improvements in Speed-Changers, of which the following is a specification.

This invention, pertaining to improvements 10 in speed-changers of that type in which rotary motion is transmitted by friction between the face of a rotating plate and the periphery of a disk, the rate of speed being adjusted by shifting radially the point of contact on the 15 plate, will be readily understood from the following description, taken in connection with the accompanying drawings, in which—

Figure 1 is a vertical section in a plane coinciding with the axis of the plates of a speed- 20 changer exemplifying my present invention; Fig. 2, a vertical section of the same in a plane at right angles to the axis of the plates; Fig. 3, a plan of one of the plate-bearings; and Fig. 4 a plan, enlarged, of the eye of the tension member.

In the drawings, 1 indicates the general fixed housing of the structure taking the form in the illustration of a drum-like casing; 2, a removable bonnet forming one of the face- 30 walls of the housing; 3, open hubs projecting outwardly from the center of the face-walls of the housing; 4, one of the two shafts of the system, which shaft for the purposes of this specification will be considered as the 35 driven shaft—that is to say, the final shaft of the apparatus—this shaft being journaled in the housing with its axis intersecting that of the housing, the upper portion of this shaft being the one from which the power is to be 40 taken off in the arrangement illustrated; 5, a step-bearing carried by the lower portion of the housing for the lower end of the shaft; 6, the main disk, splined on the driven shaft above the axis of the housing, this disk being illustrated as of usual construction involving 45 rings of leather or the like between clamp-plates; 7, a rack-sleeve forming the upper bearing for the driven shaft and arranged to slide through a bearing in the upper portion

of the housing, this rack-sleeve having its 50 lower end swiveled to main disk 6, so that the vertical adjustment of the rack-sleeve adjusts the main disk to and from the axis of the housing; 8, a pinion mounted in the housing and engaging the rack-sleeve and provided 55 with a hand-wheel, the pinion thus serving in vertically adjusting the main disk, the bearing in which the rack-sleeve slides being split and provided with a clamp-screw to hold the parts in adjusted position, as usual in devices 60 of this general class; 9, an oil-saucer on the upper portion of the main disk around the rack-sleeve, serving to receive oil and deliver it to the swivel-joint coupling the foot of the non-rotary rack-sleeve to the main disk; 10, 65 the secondary disk, similar in construction to the main disk and disposed in the same axial line, but below the axis of the housing, this disk being a non-adjustable disk vertically supported by the housing, but not otherwise journaled, the bore of its hub being entirely free of that portion of the driven 70 shaft passing through it; 11, an oil-saucer carried by the driven shaft over the hub of the secondary disk and serving to receive oil 75 coming down the driven shaft from above and to discharge it through the hub of the secondary disk to the lower hub-bearing thereof and to the step-bearing of the driven shaft; 12, an oil-saucer upon the upper face of the 80 secondary disk to serve in catching such oil as may be delivered outwardly from above the hub of this disk and to deliver that oil through a drain-channel into the lower waste-spaces of the housing; 13, plate-bearings 85 articulatedly mounted in the open hubs of the housing; 14, plate-hubs turning in these bearings; 15, a clutch at the outer end of one of the plate-hubs to serve for connection with the driving-shaft of the system, this clutch 90 being illustrated as of the jaw type, so that the driving-shaft will have a flexible connection with the plate-hub on which this clutch is provided; 16, the main plate, fast on the inner end of the plate-hub carrying the clutch 95 15, this plate having an inner flat face engaging the periphery of the two disks; 17, trunnions articulately supporting the plate-bear-

ings in the open hubs of the housing, the axes of these trunnions being at right angles to the axis of the driven shaft; 18, the secondary plate, similar to the main plate and 5 similarly mounted, but engaging that portion of the disk opposite that engaged by the main plate; 19, a tension-rod stretching across the housing in the axial line of the plates to serve in drawing the plates forcibly to the 10 disks, this tension-rod having at its mid-portion an eye loosely surrounding the driven shaft; 20, a ball-bearing carried by the tension-rod within the hub of the main plate, this ball-bearing comprising the usual pair of 15 race members with balls between them, both members being loose on the tension-rod; 21, a globular bearing-joint between the inner member of ball-bearing 20 and the plate-surface on which it bears, the tension-rod having 20 an outer nut and washer between which and the plate the ball-bearing is held; 22, a hand-wheel threaded on the secondary end of the tension-rod exterior to the housing to serve in pressing the plates to the disks; 23, 25 a collar splined upon the tension-rod just inwardly of hand-wheel 22, this collar having a globular inner face; 24, a ball-bearing, similar to the one before considered, disposed between collar 23 and the outer end of the 30 hub of the secondary plate, this ball-bearing being free of the tension-rod, and 25 a pin projecting from collar 23 and engaging a slot in the plate-bearing in which that collar is disposed, this pin-and-slot arrangement permitting 35 movement of the collar endwise of the tension-rod, but restraining its rotation.

Devices of this class have generally misbehaved, because of the inability of the plates to properly adapt themselves to the disks, erratic construction, varying compressibility, and varying wear on the part of the disks, resulting in conditions not to be satisfied if the faces of the plates are rigidly held in parallel relationship. In the present construction the rocking of the plate-bearings 40 permits the plates to assume non-parallel positions to accommodate the disks and without imposing bending strains upon the driven shaft. The secondary disk is so far as the 45 plates are concerned a floating disk without lateral influence on the driven shaft and capable of lateral shifting relative to the primary disk which is the controlling element of fixed lateral position. The transmitted speed 50 is varied in an obvious manner by shifting the primary disk radially upon the plates. The secondary disk is preferably mounted in a position corresponding with the mid-position of the primary disk. 55 It is of high importance in devices of this class with disk edges or plate-faces of leather or analogous material that oil be kept away from the points of driving contact, and it will be noted that in the present construction 60 the saucer and drainage system provides for

adequate lubrication of the parts on the driving-shaft along with satisfactory protection for the frictional driving-points.

The mechanism for adjusting the squeeze of the plates upon the disks while itself non-rotary is self-contained within the rotary-plate system and acts by tension without independent pressure abutment. The thrust due to the squeeze is taken by the ball-bearings, and the globular system of mounting the tension-rod 75 within the plate-hubs permits the rod to accommodate itself to the varying plate positions. Globular bearing 21, while subject to constant rocking in all directions relative to the main plate, is not a rotary bearing—that is to say, the plate member of the ball-bearing and the plate itself do not or at least need not turn relative to each other. This globular bearing provides flexibility between the tension-rod and the main plate, the 80 two members of the ball-bearing at this point rocking with the tension-rod. The ball-bearing 24 at the other end of the tension-rod rocks with the secondary plate instead of with the rod, globe-faced collar 23 providing for 85 the rocking of this plate relative to the rod and also for the lateral shifting of the parts relative to each other. Collar 23 being splined on the rod and to the plate-bearing prevents the rotation of the rod, the pin-and-slot arrangement connecting the collar with the bearing serving to permit the relative rocking of the rod and the bearing and the plate carried by the bearing. 90

I claim as my invention—

1. In a speed-changer, the combination, substantially as set forth, of a shaft, a pair of rotary plates with their faces opposing and on opposite sides of the axis of said shaft, bearings providing journal-support for said plates, a pivotal support for one of said bearings arranged to permit one of the plates to rock relative to the other upon an axis at right angles to said shaft, a disk carried by said shaft between the faces of the plates, means for shifting said disk radially upon the plates, a secondary disk between the plates on the opposite side of the axis of the plates and with its axis substantially in line with the first disk, mechanism for urging the plates forcibly to the disks, and a coupling connected with one of the plates for the reception of a second shaft. 100

2. In a speed-changer, the combination, substantially as set forth, of a shaft, a pair of rotary plates with their faces opposing and on opposite sides of the axis of said shaft, bearings providing journal-support for said plates, a pivotal support for said bearings arranged to permit the plates to rock relative to each other upon axes at right angles to said shaft, a disk carried by said shaft between the faces of the plates, means for shifting said disk radially upon the plates, a secondary disk between the plates on the opposite side of the axis of 110

the plates and with its axis substantially in line with the first disk, mechanism for urging the plates forcibly to the disks, and a coupling connected with one of the plates for the reception of a second shaft.

3. In a speed-changer, the combination, substantially as set forth, of a shaft, a pair of rotary plates with their faces opposing and on opposite sides of the axis of said shaft, bearings providing journal-support for said plates, a pivotal support for one of said bearings arranged to permit one of the plates to rock relative to the other upon an axis at right angles to said shaft, a disk carried by said shaft between the faces of the plates, means for shifting said disk radially upon the plates, a secondary disk between the plates on the opposite side of the axis of the plates and with its axis substantially in line with the first disk and mounted to shift to positions eccentric to the first disk, mechanism for urging the plates forcibly to the disks, and a coupling connected with one of the plates for the reception of a second shaft.

4. In a speed-changer, the combination, substantially as set forth, of a shaft, a pair of rotary plates with their faces opposing and on opposite sides of the axis of said shaft, bearings providing journal-support for said plates, a pivotal support for one of said bearings arranged to permit one of the plates to rock relative to the other upon an axis at right angles to said shaft, a disk carried by said shaft between the faces of the plates, means for shifting said disk radially upon the plates, a secondary disk between the plates on the opposite side of the axis of the plates and with its axis substantially in line with the first disk, a tension-rod connecting the two disks at their axes, a nut upon said rod for urging the plates forcibly to the disks, and a coupling connected with one of the plates for the reception of a second shaft.

5. In a speed-changer, the combination, substantially as set forth, of a shaft, a pair of rotary plates with their faces opposing and on opposite sides of the axis of said shaft, bearings providing journal-support for said plates, a pivotal support for one of said bearings arranged to permit one of the plates to rock relative to the other upon an axis at right angles to said shaft, a disk carried by said shaft between the faces of the plates, means for shifting said disk radially upon the plates, a secondary disk between the plates on the opposite side of the axis of the plates and with its axis substantially in line with the first disk, a tension-rod connecting the two disks at their axes, a nut upon said rod for urging the plates forcibly to the disks, flexible unions between the tension-rod and the plates, and a coupling connected with one of the plates for the reception of a second shaft.

6. In a speed-changer, the combination, substantially as set forth, of a shaft, a pair of ro-

etary plates with their faces opposing and on opposite sides of the axis of said shaft, bearings providing journal-support for said plates, a pivotal support for one of said bearings arranged to permit one of the plates to rock relative to the other upon an axis at right angles to said shaft, a disk carried by said shaft between the faces of the plates, means for shifting said disk radially upon the plates, a secondary disk between the plates on the opposite side of the axis of the plates and with its axis substantially in line with the first disk, a tension-rod connecting the two disks at their axes, a nut upon said rod for urging the plates forcibly to the disks, ball-bearings between the tension-rod and the plates, and a coupling connected with one of the plates for the reception of a second shaft.

7. In a speed-changer, the combination, substantially as set forth, of a flexible shaft, a pair of rotary plates with their faces opposing and on opposite sides of the axis of said shaft, bearings providing journal-support for said plates, a pivotal support for one of said bearings arranged to permit one of the plates to rock relative to the other upon an axis at right angles to said shaft, a disk carried by said shaft between the faces of the plates, means for shifting said disk radially upon the plates, a secondary disk between the plates on the opposite side of the axis of the plates and with its axis substantially in line with the first disk, mechanism for urging the plates forcibly to the disks, a coupling connected with one of the plates for the reception of a second shaft, and oil-saucers having channels to convey oil vertically through said disks.

8. In a speed-changer, the combination, substantially as set forth, of a housing, a vertical shaft journaled in said housing, horizontal plate-bearings carried by the housing on opposite sides of said shaft, trunnions connecting said bearings and the housing and having their axes at right angles to said shaft, plates having hubs mounted to rotate and slide in said bearings, a tension-rod connected articulately with the two plates and provided with means for drawing the plates toward each other, a disk carried by said shaft between the plates, means for adjusting said disk radially upon the plates, a secondary disk supported by the housing between the plates on the side of the plate-axis opposite the first disk, and a coupling connected with one of the plates for the reception of a second shaft.

9. In a speed-changer, the combination, substantially as set forth, of a housing, a vertical shaft journaled in said housing, horizontal plate-bearings carried by the housing on opposite sides of said shaft, trunnions connecting said bearings and the housing and having their axes at right angles to said shaft, plates having hubs mounted to rotate and slide in said bearings, a tension-rod connected articulately with the two plates and provided with

means for drawing the plates toward each other, a disk carried by said shaft between the plates, means for adjusting said disk radially upon the plates, a secondary disk supported by the housing between the plates on the side of the plate-axis opposite the first disk and free from lateral restraint except by the plates, and a coupling connected with one of the plates for the reception of a second

10 shaft.

10. In a speed-changer, the combination, substantially as set forth, of a shaft, a pair of rotary plates with their faces opposing and on opposite sides of the axis of said shaft, bearings providing journal-support for said plates, a pivotal support for one of said bearings arranged to permit one of the plates to rock relative to the other upon an axis at right an-

gles to said shaft, a disk carried by said shaft between the faces of the plates, means for shifting said disk radially upon the plates, a secondary disk between the plates on the opposite side of the axis of the plates and with its axis substantially in line with the first disk, a tension-rod articulately coupled to the two plates, a collar splined on the rod and serving as part of the coupling system, a nut threaded upon the rod exterior to said splined collar, and a pin-and-slot provision between said collar and one of said bearings to serve in preventing the rotation of said collar and rod.
